TRAILING WIRE ANTENNA

Ralph O. Robinson, Jr., Silver Spring, Md., assignor to the United States of America as represented by the Secretary of the Navy

Filed Aug. 1, 1952, Ser. No. 302,091

5 Claims. (Cl. 102—70.2)

This invention relates to antenna systems for use with projectiles. The oscillator acts both as a transmitter means which has the effect of substantially increasing the electrical length of a projectile, thereby making possible a projectile fuze having certain advantages over existing fuzes.

One of the most reliable devices for detonating an explosive projectile in the proximity of a target is the radio proximity fuze. In its basic form, this fuze consists of a proximity sensitive radio frequency oscillator and associated amplifiers, and a firing circuit, all built into the projectile. The oscillator acts both as a transmitter and receiver and is coupled to the projectile casing in such a manner as to cause the latter to act as a radiator. When the transmitter is operating, that is, after the projectile has been fired, a radio frequency signal provided by the oscillator is emitted from the projectile. A target reflects parts of this signal back to the projectile where it reacts upon the oscillator. If the reflected waves are out of phase with the transmitted waves, the oscillator load is increased, thereby increasing the current in the oscillator's plate circuit; while if the reflected waves are in phase, the oscillator load is decreased thereby decreasing the current in the oscillator's plate circuit. The oscillatory plate current generated in this manner produces a pulse which, when amplified, is utilized to actuate the firing circuit of the projectile.

The characteristics of the radiating system are an important part of this arrangement inasmuch as they determine the range of suitable operating frequencies and the sensitivity of the fuze. Various antenna constructions have been employed in the past. The invention operates in conjunction with a conventional nose excited type of projectile in which oscillatory currents are caused to flow over the entire surface of the projectile body.

It is the primary object of this invention to provide a means for substantially increasing the effective electrical length of the projectile and thus provide better radiation resistance and pattern characteristics than were previously obtainable.

It is a further object of the invention to provide a radiating system for a projectile that permits a greater spread of operating frequency for the projectile fuze, thereby reducing the success of enemy counter-measures in prematurely detonating or jamming the fuze. In the case of proximity fuzed projectiles being used against ground targets, an additional advantage realized by increasing the spread of operating frequency is that the use of a low RF frequency reduces the number of cycles of the signal occurring during the time the fuze can fire, thereby reducing the dispersion of burst height in fuzes. That is, the number of reflected signal waves of sufficient intensity to actuate the fuze are reduced, for limiting the range over which the fuze will be fired.

The invention also has for an object the provision of means by which greater fuze sensitivity may be achieved, with the result that the distance from the target at which a projectile will detonate may be increased. This is also of particular importance in the application of proximity fuzes to the smaller projectiles.

Another important object of the invention is to provide a radiating system by means of which standardization of fuze operating frequency and sensitivity may be

2

achieved. This standardization is made possible by substantially increasing the effective electrical length of the shorter projectiles so that all projectiles have the same electrical length.

5 Briefly, these and other objects are achieved by providing a trailing wire electrically connected to the base of a projectile which has conventional nose excitation, and means adjacent the projectile base for packaging the wire so that it will be automatically projected from the rear of the projectile upon firing of the latter.

Other objects and many of the attendant advantages of this invention will be readily appreciated as the same becomes better understood by reference to the following detailed description when considered in connection with the accompanying drawings wherein:

FIG. 1 is a diagrammatic view showing trailing wires applied to projectiles of different sizes;

20 FIG. 2 is an enlarged view showing in section some of the components of a proximity fuze in the nose of a projectile, the projectile itself being shown in side elevation;

25 FIG. 3 is an enlarged partial cross section through the base of a proximity fuzed projectile, showing the trailing wire packaged in the projectile base;

30 FIG. 4 is a view similar to that of FIG. 3, but showing the trailing wire released; and

FIG. 5 is a sectional view on the line 5—5 of FIG. 3.

Referring to FIG. 2, the invention is shown applied to a conventional projectile 10. The projectile 10 has a casing 12 and a rotating band 14. The projectile carries the usual explosive charge, indicated at 16 in FIGS. 3 and 4. A proximity fuze, generally similar to the one disclosed in co-pending application, Serial No. 471,388, filed January 6, 1943, M. A. Tuve et al., inventors, is carried in the nose of the projectile; however, only so much of the fuze is shown in FIG. 2 as is necessary for an understanding of the present invention. Thus, the projectile is shown as having a plastic nose piece 18 which is fitted to a cylindrical housing 20 which is itself carried in a second cylindrical housing 22 threaded into a bore provided in the projectile casing 10. Shield cans 24 and 26, which house the oscillator components and the amplifier components, respectively, of the fuze circuit, are fitted, together with the other components not shown, into the plastic nose piece 18 and the cylindrical housing members 20 and 22.

The vacuum tube employed in the oscillator circuit of the fuze is shown at 28 as being positioned centrally of the shield can 24. A tube 33 of insulating material, which serves as the form on which the tank coil 32 of the oscillator circuit is wound, is fitted around the vacuum tube 28. These circuit elements, and others not shown, are held in place in shield can 24 by means of a potting compound 34. One terminal of the coil 32 is connected to the nose cap exciter 36 fitted in the nose piece 18, while the other terminal of the coil is connected to common at the bottom of the shield can 24.

60 A trailing wire 40, electrically connected to the projectile casing 10 and the tank coil 32, is carried at the base end of the projectile. The wire 40 may itself be a bare or an insulated conductor. As can be seen in FIGS. 3 and 4, a threaded bore is provided in the projectile base to receive a cylindrical housing 42 sealed in place by a lead seal 44. The housing 42 has an end plate 46 which is releasably held on the housing by two or more spring pressed detents 48 carried in apertures in the housing. While the projectile is stationary the detents 48 are urged into apertures in the plate 46 by the springs 55. However, when the projectile is fired, the centrifugal force developed by its rotation urges the detents outwardly thereby freeing the plate. A compressed spring

52 held in position in the housing 42 by the circular ridge 54 formed on the inner surface of the housing bears on the plate 46 to force the latter free of the housing 42.

The wire 40 is coiled in the housing by a well known technique involving imparting a twist to the individual turns of wire so that the wire uncoils when released. The wire is fastened at one end to an eye 56 provided in the housing. As can best be seen in FIG. 5, a slot 58 is provided in the ridge 54 so that the last turn of the wire can be led to the eye 56 and fastened without being kinked over the ridge. At its free end the wire carries a drag ball 60 which assists in uncoiling the wire 40 and holding it in its trailing position. A recess 62 and a channel 64 leading to the recess are provided in the plate 46 to accommodate the drag ball and the adjacent partial turn of the antenna wire.

While the manner in which the wire 40 is fed from the housing 42 into a trailing position behind the projectile is for the most part apparent, a brief explanation of this aspect of the operation of the invention follows. Referring again to FIG. 3, the wire 40 is shown packaged in the housing 42 and held in that position by the plate 46. Upon the projectile's being fired, the detents 48 are moved outwardly by the centrifugal force developed by rotation of the projectile; however, the plate 46 remains in the position shown in FIG. 3, because the pressures developed at firing act on the plate as long as the projectile is in the barrel. After the projectile is freed, the spring 52 expels the plate 46, and the wire begins to uncoil as shown in FIG. 4. Friction on the drag ball 60, and the twist imparted to wire 40 by the coiling technique, cooperate to extend the wire into trailing position along the axis of the projectile as shown in FIG. 1.

The manner in which the trailing wire 40 serves to increase the effective electrical length of the projectile, thus enabling standardization of fuses, can be seen by reference to FIGS. 1 and 2. The wire 40 is electrically connected to one terminal of the oscillator tank coil through the shield cans 24 and 26, the projectile casing 10, and eye 56. With this arrangement, the nose cap exciter 36 will excite the projectile casing 10 and the wire 40 so that the casing and the wire form the main part of the radiating system. In FIG. 1, projectiles 10 and 10a of different sizes are shown provided with wires 40 and 40a of different lengths so that the effective electrical lengths of the combined projectiles and trailing wires are the same. The advantages realized from the standardization of operating frequency and fuse sensitivity of this invention are apparent when it is considered that a single fuse having identical components can be incorporated into projectiles of various sizes ranging from 75 mm. to 240 mm.

Modifications of the invention will occur to those skilled in the art. Thus, it may be desirable in some cases to coil the wire around the projectile body rather than inside the projectile base as shown. Also, while spring pressed detents have been disclosed to retain the wire in coiled position, a solder or plastic means which could be melted or burned could be employed to perform that function.

Obviously many other modifications and variations of the present invention are possible in the light of the above teachings. It is therefore to be understood that within

the scope of the appended claims the invention may be practiced otherwise than as specifically described.

What is claimed is:

1. In a projectile having a proximity fuze, said projectile having a base, the combination comprising a housing carried in the base, a coiled wire in said housing, said coiled wire having a twist imparted thereto whereby the wire tends to uncoil when released, one end of said wire being electrically connected to said housing, drag means carried on the other end of said wire, means for retaining said wire in coiled position in the housing, said means including a plate releasably held in the housing so that upon removal of said plate said wire will extend from the projectile, and means operable by centrifugal force for releasing said plate.

2. In a projectile having a nose proximity fuze, said projectile having a base, said fuze including an oscillator circuit having a tank coil, said tank coil being electrically connected to the nose of said projectile, the combination comprising a housing carried in the base, a coiled wire in said housing, one end of said wire being electrically connected to said housing, and means for releasably retaining said wire in coiled position in the housing so that upon removal of said retaining means said wire will extend from the projectile.

3. In a projectile having a proximity fuze, said projectile having a base, said fuze including an oscillator circuit having a tank coil, a housing carried in the base, said tank coil being electrically connected by means of the projectile body to said housing, a coiled wire in said housing, one end of said wire being electrically connected to said housing, means for releasably retaining said wire in coiled position in the housing, and means for expelling said wire from said housing into trailing position at the rear of said projectile.

4. In a projectile having a proximity fuze, said projectile including a casing of electric current conducting material, said proximity fuze including an oscillator having a tuned circuit, means connected to said tuned circuit for coupling the electromagnetic energy generated by said oscillator to said casing whereby the latter is caused to radiate said energy, and an extensible conductor connected to said projectile casing, said extensible conductor being adapted to be carried in trailing relationship at the rear of said projectile, thereby increasing the effective electrical length of said projectile.

5. In a projectile having a proximity fuze, said projectile including a casing of electric current conducting material, said proximity fuze including an oscillator having a tuned circuit, means connected to said tuned circuit for coupling the electromagnetic energy generated by said oscillator to said casing whereby the latter is caused to radiate said energy, a housing in said projectile casing, an extensible conductor carried in said housing and electrically connected to said projectile casing, and means for ejecting said conductor into trailing position at the rear of said projectile, thereby increasing the effective electrical length of said projectile.
